CLAIM

I claim the ornamental design for a connector, as shown and described.

DESCRIPTION

FIG. 1 is a perspective view of a connector.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is an additional perspective view thereof.

The broken lines show portions of the connector that form no part of the claimed design.
